UNITED STATES PATENT OFFICE.

FREDERICK M. RAMSDELL, OF WORCESTER, MASSACHUSETTS.

HAND-TOOL.

1,382,932.

Specification of Letters Patent. Patented June 28, 1921.

Application filed April 15, 1920. Serial No. 374,082.

To all whom it may concern:

Be it known that I, FREDERICK M. RAMSDELL, a citizen of the United States, residing at Worcester, in the county of Worcester 5 and State of Massachusetts, have invented a new and useful Hand-Tool, of which the following is a specification.

This invention relates to a device for use in small shops, more especially repair shops, 10 and in connection with home repair kits and job shops, for use in performing certain necessary and very common machine shop operations without the use of the ordinary machine shop equipment. The chief objects 15 are to provide a simple and convenient tool holder for use in holding a tool stationary if the operator has a lathe or other machine for rotating the work, or if he does not, for rotating the tool while the work is held in a vise; to provide an improved support for a tool for cutting a taper on the end of a piece of work, suitable for use with the above mentioned tool holding device; also to provide an improved guide for the work 20 25 coöperating with the tool holder in such a way as to properly center it with respect to the work; and to provide an improved form of nurling attachment to be used in connection with the same equipment. The invention also involves improvements in 30 various details of the above mentioned features.

Reference is to be had to the accompanying drawings in which—

35 Figure 1 is a plan of a tool holder and a taper cutting tool mounted thereon constructed in accordance with this invention;

Fig. 2 is an end view of the same;

40 Fig. 3 is a side view of the tool and its immediate support;

Fig. 4 is a central sectional view of the same on the line 4—4 of Fig. 1;

Fig. 5 is a plan of the tool holder proper;

45 Fig. 6 is a central sectional view of the same;

Fig. 7 is a bottom plan view thereof;

Fig. 8 is a plan of the centering disk;

Fig. 9 is a side view showing the work and the manner in which it is centered by said 50 disk and illustrating a die in position for cutting a thread thereon;

Fig. 10 is a plan of the die;

Fig. 11 is a plan of a nurling attachment

constructed in accordance with this invention;

55

Fig. 12 is an end view of the same showing how the work is supported in a vise;

Fig. 13 is a view of the opposite end of the nurling attachment detached from the tool holder;

60

Fig. 14 is a side view of the same;

Fig. 15 is a bottom plan of the plate for supporting the nurling tool arms;

Fig. 16 is a sectional view on the line 16—16 of Fig. 15, and

65

Fig. 17 is a view of the work performed on this device showing the guiding means thereon in central section.

As stated above this invention is designed for use in small job shops and other places 70 where machinery is not available for performing certain common metal working operations. It can be used for cutting threads, cutting tapers, nurling, and various other operations, but these three uses are the 75 ones illustrated in the drawings. It will be understood without further comment that either the work may rotate or the tool, the other being stationary. If a lathe is at hand the work is applied to it so as to rotate and 80 the work holder is held against rotation and fed along the work if necessary by hand, but I have illustrated the invention as being used where no such rotating device is at hand and I have shown the work in the form of a screw A as being held in a vise B, so that 85 it will be necessary therefore in that case to rotate the tool, this being done by hand as in the case of the ordinary cutting of a thread with a die and hand die plate.

90

In all the forms illustrated a tool holder is shown which involves two halves 10 and 11. These two halves or clamping members are provided with perforations located at equal distances from the center and on opposite sides of the center and parallel with each other, one of the perforations in each one having a screw thread for receiving the screw threaded portion of reduced diameter as 100 will be obvious, leaving a shoulder for abutting against the outer surface of the member 10 or 11. Therefore by turning the two handles the two clamping members 10 and 11 can be moved toward and from each 105 other. These two handles are knurled to per-

mit of their being used in this way and they project in opposite directions but at a distance apart from the opposite sides of the tool holder itself as shown more clearly in Fig. 1. These handles are used to clamp the device in position so as to hold the tool that is to be used and also to hold a centering and guiding disk 14 in a cylindrical recess 15 at one end of the tool holder. The other end of the tool holder also has a similar recess 16 which is adapted for receiving a projection or element of a similar shape connected with the metal working tool itself. In its simplest application this will receive a die 17 for cutting a thread; this die having a flat cylindrical shape. This device with a tap applied thereto can be used as a tap wrench.

In the use of the device for cutting a thread therefore the tool holder is clamped up on the two disks 14 and 17 located respectively in the recesses 15 and 16 and they occupy the relative positions shown in Fig. 9. Being clamped normally in position they partake of all the movements of the tool holder and while the central passage in the disk 14 fits the work A the die will cut a thread thereon by the ordinary act of turning the tool holder. The disk 14 and die 17 are spaced apart and both rotate about the work which they fit. This forms a centering and guiding device for insuring the accuracy of the work, something that is not present in the ordinary thread cutting die.

Similar functions and operations take place in the use of this instrument no matter what the tool may be that is applied to it. Referring now again to Figs. 1, 2, 3 and 4 the die 17 is replaced by a projection 20 of the same size and shape as the outline of the die and extending from a work support 21. This projection holds the work support when the handles 12 are clamped up in position and the disk 14 also clamped in place in the same way as shown in connection with Fig. 9. This work support in addition, however, is provided with another recess 22 which holds a second disk 24 like the disk 14, including the central perforation. These two disks therefore serve to center and guide the work with respect to the tool holder in a manner similar to that indicated in Fig. 9. The disk 24 is held in position by a screw 23 or in any other desired way.

On the tool holder 21 is a surface 25, preferably inclined. Back of this surface there is an integral projection 26 extending up above it and provided with a pin 27 in its edge and with an adjusting screw 28 extending through it. The pin 27 and screw 28 are spaced materially apart.

On the opposite side is a similar projection 29 having two adjusting and holding screws 30. The cutting tool 31 is intended 65 to be held between the four points repre-

sented by the parts 27, 28, 30 and 30. These obviously can be adjusted in such a way as to bring the tool to the desired position.

In the form indicated the tool 31 is provided with a cutting edge 32 which, on account of the inclination of the tool and the angle at which the edge is cut, will produce a taper α on the end of the work A. In order to do this the tool is properly adjusted as to angle and location, preferably with one edge substantially radial with respect to the work. The tool support 21 is clamped in the tool holder 10—11 as has been described above, the disk 24 first being secured in position on the work support and the disk 14 on the tool holder. This structure involving the tool, tool support, and tool holder, is then applied to the work as indicated in Fig. 2. The work is centered by the passages through the disks 14 and 24 and then either the work or the tool holder is rotated. The result will be the production of a tapered end α on the work.

It will be noticed that the other end of the tool 31 is shown as having an edge 33 which can be inclined the same way as the edge 32 if desired so as to permit of reversing the cutting tool when it is worn or, as shown, it may be shaped so as to permit the cutting off of the end of the work at a right angle. 95 It is necessary in the form shown to turn the tool around and turn it over 90 degrees in order to use this particular tool for that purpose. It will be understood that this tool 31 is merely illustrative and that tools 100 of any desired shape and having all kinds of edges can be used with this invention to produce the desired results.

On the second sheet of drawings I have shown the same tool holder in all details 105 and illustrated it as used for operating a nurling attachment. In this case the nurling attachment comprises a plate 41 having a circular recess 42 therein for receiving the detachable disk 24 with a perforation therethrough. This is inserted in the recess and need not be clamped therein in view of the construction. The plate has a cylindrical projection 40 concentric with the recess 42 and adapted to be received in the recess 16 of the tool holder for the same purpose as the projection 20 above described. The disk 14 is also used as before. This permits of the rotation of the plate 41 about the work as a center.

The plate 41 is provided with two perforations in which are placed pivot screws 45 on which are pivoted arms 46 each provided with a nurling wheel 47 rotatably mounted thereon. One arm has a swinging pivot screw 48 pivoted thereto and projecting through a perforation in the other arm. It has an adjusting nut 49 on the end for forcing the two nurling rolls toward each other as much as may be desired. These 130

parts being applied to the tool holder and centered on the work by means of the disks 14 and 24 which center and guide the parts, the rotation of the tool holder with its 5 nurling tool thereon about the stationary work will result in providing a knurled surface at a^2 on the work.

I have not illustrated all the tools that can be used in connection with this device 10 as it will be understood that within the scope of this invention many others can be provided. It will be seen that this simple arrangement furnishes an accurate and mechanical construction for use under the 15 conditions above mentioned for the purpose of performing any of the simple metal working operations that do not require too deep a cut. The work and tool holder are accurately centered and guided with respect 20 to each other on account of the distance apart of the guiding disks which I have described. This enables many individuals to make repairs and also even make screws and other small articles at their homes or in 25 small repair shops without the necessity of installing any expensive equipment. As a matter of fact even if they do have the equipment this device is more easily set up than would be the case with certain kinds 30 of machinery and will be found useful where only one or a small number of parts are to be made even in shops that do have machinery suitable for manufacturing.

Although I have illustrated and described 35 only three uses for this device and shown only a single construction of the tool holder proper I am aware of the fact that it can be applied to other uses and that modifications can be made in the parts without departing 40 from the scope of the invention as expressed in the claims, and I do not wish to be restricted in these respects except as specified therein.

What I claim is:—

45 1. As an article of manufacture, a hand tool comprising a pair of complementary clamping members, a pair of handles each having a screw thread, said members each having two parallel openings located on opposite sides of the center, one of each pair being screw-threaded, for receiving the screw threaded portions of said handles so that said members are clamped together thereby, said handles extending in opposite 50 directions from opposite sides of said members, said members having concave jaws at one end adapted to receive and clamp a cylindrical holding surface of a metal working tool, a similar pair of jaws at the other end, 55 and a circular disk adapted to be held in the last named jaws and having a central passage for guiding and centering the work.

60 2. As an article of manufacture, a hand tool comprising a complementary pair of members, each having a clamping jaw on

each end, the two jaws at the same end of the tool being arcuate, concentric, and of the same size, a centrally perforated circular guide disk located in one pair of jaws, a circular projection located in the other, and a 70 pair of spaced oppositely projecting handles for forcing said members together and clamping the jaws against the disk and projection, a second centrally perforated guide disk carried centrally by said projection, 75 said perforation through said disks constituting means for centering and guiding the work, and means connected with said projection for carrying a metal working tool.

3. The combination with a hand tool comprising a pair of complementary members, a pair of handles located on opposite sides of the center for clamping said members together, said members having concave jaws at one end and a similar pair of jaws at the 80 other end, of a circular disk adapted to be held in the last named jaws and having a central passage for guiding and centering the work, and a metal working tool having a centrally perforated central projection fitting in the first named jaws and adapted to 85 be clamped thereby.

4. The combination of a clamping device having a central recess in each end, said recesses being spaced from each other longitudinally, of a guide disk clamped in one of said recesses and having a perforation at the center for fitting the work on which it is to be used and guiding it, a centrally perforated cylindrical projection adapted to fit in 90 the other of said recesses and provided with a guide centrally located therein for fitting the surface of the work, a tool connected with said projection for operation on the work, and handles projecting from said clamping device for manipulating it and the tool and clamping said disk and projection in said 95 recesses.

5. The combination of a clamping device having a central recess in each end, said recesses being spaced from each other longitudinally, and a guide disk clamped in one of said recesses and having a perforation at the center for fitting the work on which it is to be used and guiding it, of a tool support 110 having a centrally perforated cylindrical projection adapted to fit in the other of said recesses, a second guide disk centrally secured thereto for fitting the surface of the work, a tool mounted on said support for operation on the work, said tool support having a surface on which the tool is adapted to be mounted and provided with adjusting means at the side thereof for adjusting the position of the tool therein and clamping it 115 thereto.

6. The combination of a clamping device having a cylindrical recess in each end, a guide disk clamped in one of said recesses and having a perforation at the center, a 120

metal working tool support having a centrally perforated cylindrical projection adapted to fit in the other of said recesses and provided with a second guide disk centrally secured thereto, and having a tool mounted thereon for operation on the work, said guide disk being spaced apart for fitting the work on which they are to be used and guiding it, and a cutter mounted on said tool support.

7. The combination of a clamping device, a work guide clamped at one end thereof, a metal working tool support having a centrally perforated cylindrical projection clamped at the other end of said device, a second guide centrally secured thereto for fitting the surface of the work, handles projecting from said device for manipulating it and clamping the first named guide and

projection in position, and a taper cutter 20 mounted on said support at an inclination and having an inclined cutting edge.

8. The combination of a clamping device, a guide disk clamped therein and having a perforation at the center for fitting the work 25 on which it is to be used, a metal working tool support clamped by the other end of said device, a guide centrally secured thereto for fitting the surface of the work, said clamping member having handles projecting therefrom for manipulating it, and a cutter adjustably and reversibly mounted on said support and having a cutting edge for determining the shape to be cut on the work.

In testimony whereof I have hereunto 30 affixed my signature.

FREDERICK M. RAMSDELL.
